(57) **CLAIM**

The ornamental design for a diverter valve, as shown and described.

DESCRIPTION

FIG. 1 is a top perspective view of a diverter valve showing our new design;

FIG. 2 is a left side elevational view, the right side elevational view being a mirror image thereof;

FIG. 3 is a front elevational view, the rear elevational view being a mirror image thereof;

FIG. 4 is bottom plan view thereof; and,

FIG. 5 is a top plan view thereof.
